UNITED STATES PATENT OFFICE.

EDWIN N. LIGHTFOOT, OF WAUWATOSA, WISCONSIN, ASSIGNOR TO THE CUTLER-HAMMER MFG. CO., OF MILWAUKEE, WISCONSIN, A CORPORATION OF WISCONSIN.

ELECTRIC HEATER.

Application filed July 15, 1927. Serial No. 205,987.

This invention relates to electric heaters.

More particularly the invention relates to heaters of the type disclosed in United States Letters Patent of C. C. Abbott No. 5 1,494,939 issued May 20, 1924, this type of heater comprising a sinuous resistor confined between two metal plates which form heat dissipating vanes for the resistor which preferably is in the form of a helix extending 10 longitudinally of the plates.

As will be understood, the resistor must be insulated from the enclosing plates whereas it is desirable to afford a maximum degree of heat conductivity from the resistor to the plates and hence the employment in the Abbott heater of a highly refractory powdered insulation compacted to a hard dense mass. The Abbott heater comprises a so-called tubular heater provided with heat 20 dissipating vanes.

The present invention has among its objects to provide a similar tubular heater equipped with vanes, but of simpler construction.

25 A further object of the present invention is to construct such a heater in a manner to avoid the necessity of compacting the insulation about the resistor by externally applied pressure.

30 Various other objects and advantages of the invention will hereinafter appear.

One embodiment of the invention is illustrated in the accompanying drawing which will now be described, it being understood 35 that the embodiment illustrated is susceptible of various modifications without departing from the scope of the appended claims.

In the drawings

Fig. 1 is a top plan view of the heater, 40 partly in section.

Fig. 2 is a side view thereof.

Fig. 3 is a sectional view taken on line 3-3 Fig. 1.

Fig. 4 is a sectional view taken on line 45 4-4 Fig. 1, and

Fig. 5 is a detail view showing a portion of the bottom plate of the heater.

Referring to the drawing, the heater illustrated is of the so-called "strip" type and 50 comprises a casing formed of two plates. One plate is a channel plate with lateral flanges, the channel portion being designated by reference character 10 and the flanges by reference character 11. This plate has end 55 flanges 12 which are continuous with the

flanges 11 and has at opposite ends of the channel 10 and in communication therewith terminal pockets 13. As will be apparent, this plate may comprise a stamping or may be formed in any other preferred manner. 60 On the other hand, the second plate designated as 14 comprises merely a flat plate having its side and end marginal portions folded over and clamped upon the flanges of the channel plate whereby said plates are 65 fastened together to form a closed casing. Preferably the plate 14 is pressed into intimate contact with the flanges 11 and 12 of the channel plate throughout the extent of such flanges whereby the casing is essentially 70 a tubular casing of relatively small diameter with heat dissipating vanes comprising said flanges and plate 14.

The tubular portion of the casing is provided to receive a helical resistor 15 attached 75 to terminals 16 fixed to the channel plate and said terminals having portions within the pockets 13 for attachment thereto of the resistor. Preferably the resistor is in mounting thereof stretched to separate its 80 turns to the desired extent. As will be apparent, the resistor must be mounted in the channel plate prior to assembly of the two plates and it is preferred to introduce the insulation for the resistor after the casing is assembled. Accordingly it is desirable 85 to provide the resistor with a number of insulating washers 17 arranged thereon in a spaced relation to center the resistor in the casing during the process of insulating the 90 resistor.

Preferably the insulation comprises magnesium oxide in a powdered or granular state or such material mixed with alundum or other chemically inert insulation in a similar state. Such material may be and preferably is introduced into the casing after assembly. To this end the plate 14 is provided with a cut tongue 18 which may be bent outwardly to afford an entrance for 100 the insulation whereas after filling it may be pressed back into position to seal the opening thus afforded.

The tongue 18 is so located as to permit the insulating material to enter one of the 105 terminal pockets from which it passes to the channel 10 and in practice filling of the channel may be and preferably is facilitated and expedited by vibrating the unit.

Assuming use of magnesium oxide or a 110

mixture as that aforementioned the same may be and preferably is subjected to chemical treatment in situ to disintegrate and redistribute the particles of magnesium oxide 5 thus producing a mass which for practical purposes is as satisfactory as a magnesium oxide compacted by externally applied pressure as in swaged tubular heaters. Moreover such chemical treatment may be effected 10 in a simple and convenient manner.

In so treating the magnesium oxide or mixture after the same is introduced into the casing it is preferred to first wet the material, which can readily be accomplished 15 by forcing or drawing water into the casing through the opening afforded by the tongue 18 or through the seams between the plates forming the casing. Also it is preferred to introduce water in such quantity 20 as to fill all voids within the casing and then to subject the filling to heat treatment.

A convenient method of thus heat treating the insulating filling is to place the unit in an autoclave, subjecting the filling to the 25 action of steam in the neighborhood of 300 degrees F. or more for a suitable period of time. Under this treatment the magnesium oxide whether used alone or mixed with a more or less inert material reacts and disintegrates with the results aforementioned 30 after which it is merely necessary to dry out the insulating filling as by heating the unit in a furnace. The heater is then ready for use.

35 The terminals 16 which in practice may be of any preferred construction are shown as comprising threaded studs each having a head 19 within its respective terminal pocket 13 and a pin 20 to which one end of 40 the resistor is adapted to be attached. As illustrated the resistor is looped about the pin and retained thereon by a washer 21, the pin being riveted over said washer. The head of each terminal stud is wrapped with 45 a sheet 22 of mica or other suitable insulating material and each stud carries a mica or other insulating washer 23 to insulate its

shank from the casing. Also each stud carries externally of the casing a clamping nut 24 having interposed between the same and the casing an insulating washer 25 of mica or other suitable material and a metal washer 26 immediately beneath the clamping nut. As will be understood, the terminal studs are adapted to be supplied with the usual nuts and washers for external circuit connection thereof.

What I claim as new and desire to secure by Letters Patent is:

1. An electric heater comprising a helical 60 resistor embedded in a mass of granular refractory insulating material and a casing therefor having a tubular section to receive said resistor and said insulating material and to confine the latter, said casing having heat 65 dissipating vanes integral with walls of said tubular section and having the walls of said tubular section in direct and intimate contact with said mass of insulating material.

2. An electric heater comprising a channel plate with integral flanges extending longitudinally therof, a cover plate for said channel plate which forms therewith a tubular casing with heat dissipating vanes comprising said flanges, granular heat refractory insulation filling said tubular casing and having intimate contact with the walls thereof and a helical resistor embedded in 75 said insulating material.

3. An electric heater comprising an elongated channel plate having integral side flanges and end flanges, a flat cover plate having its edges folded over said flanges and forming with said channel plate a tubular casing with heat dissipating vanes comprising 80 said flanges, refractory electrical insulating material filling said tubular casing and having intimate contact with the walls of 85 the latter, and a helical resistor embedded in said insulating material.

In witness whereof, I have hereunto subscribed my name.

EDWIN N. LIGHTFOOT.
